(57) **CLAIM**

I claim the ornamental design for a decorative device having a plurality of electrically lighted bundles of random length fiber optics for weaving into branches of a Christmas tree, as shown and described.

DESCRIPTION

FIG. 1 is a perspective view of a decorative device having a plurality of identical electrically lighted bundles of random length fiber optics for weaving into branches of a Christmas tree, embodying the design of the present invention, wherein only one of the plurality of electrically lighted bundles is shown for purposes of clarity.

FIG. 2 is a front elevational view thereof, the rear elevational view being identical thereto;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view showing the decorative device having a plurality of identical electrically lighted bundles of random length fiber optics for weaving into branches of a Christmas tree in use; the broken line showing of environmental structure is for illustrative purposes only and forms no part of the claimed design.
